UNITED STATES PATENT OFFICE

2,207,065

WINDOW

Maurice D. McCormick, Chicago, Ill., assignor of
one-half to Stanley Werell, Chicago, Ill.

Application October 19, 1937, Serial No. 169,839

22 Claims. (Cl. 20—48)

My invention relates to windows, and is more particularly concerned with mechanism for sealing rotary-mounted window panes.

In its more specific phases my invention contemplates a double hung or casement sash in which the pane itself is mounted in a subsash rotatably mounted in the main sash, whereby the pane together with its subsash may be turned around to facilitate washing both sides, or—in some instances—for providing ventilation also. As applied to such a construction, my invention is especially concerned with means for locking the rotatable subsash in its closed position and for sealing it against the weather. Preferably, the subsash will be pivoted to the main sash along a medial vertical line, although I contemplate that the subsash may be mounted to pivot about its edge to the main sash after the fashion of a casement sash.

I contemplate also that the member corresponding to the subsash may itself constitute the sole movable sash for the pane and be mounted in a fixed frame, rather than in a movable main sash, this being especially suited for the so-called fixed windows of air-conditioned homes and buildings.

A further object of my invention is a positioning and sealing device for the subsash cooperating with all four edges thereof but releasable by a single manual operating member when the pane is to be rotated for cleaning or ventilation. A still further object is a set of releasable sealing strips for the several edges of the subsash which, while itself light and small in size, is so mounted that it effects a firm weather seal throughout the margins of the subsash.

Still another object is a releasable locking and sealing mechanism for the subsash which can be released only by the use of a key by authorized persons, such as window cleaners or janitors, but which discourages rotation of the subsash by occupants or tenants instead of raising or opening the main sash for the purpose of ventilation.

The foregoing together with further objects, features and advantages of my invention are set forth in the following description of specific embodiments of my invention illustrated in the accompanying drawings wherein:

Fig. 1 is an inside elevation of the lower sash of a double hung window showing the rotary pane in closed position;

Fig. 2 is a similar view showing the rotary pane rotated to open position;

Fig. 3 is a plan section taken on the line 3—3 of Fig. 2;

Fig. 4 is a typical vertical transverse section through the lower rails of the main and subsashes taken on the line 4—4 of Fig. 1 but on an enlarged scale;

Fig. 5 is a section similar to Fig. 4 but taken along the axis of rotation;

Fig. 6 is a vertical section taken on a medial plane of the sash showing the upper right hand corner thereof with the sealing strip in closed position;

Fig. 7 is a section similar to Fig. 6 but showing the sealing strips in their released position; and

Fig. 8 is a view similar to Fig. 7 but on a reduced scale showing a modified form of operating mechanism for the releasable sealing strips.

I have here illustrated my invention as incorporated in the upper and lower sashes of a double hung window, although I contemplate that corresponding embodiments may be incorporated in casement sash.

The sash 10 is slidably mounted in the window frame 11 in the usual manner. The sash 10 comprises a main or outer sash 12 and a subsash or inner sash 13 mounted in the plane of the main sash and surrounded thereby. The subsash is so mounted in the main sash that it pivots about a medial vertical axis along the line 5—5 of Fig. 1, this mounting being effected by upper and lower pivot pins shown in Fig. 5, 25 as will subsequently be explained. The glass pane 14 is carried directly by the subsash, although the glazing may be subdivided into smaller panes by the usual muntins, if desired.

The body of the main sash 12 is formed by four rails 15 constituting its respective sides, top and bottom, the rails being mitered at the corners. Preferably the rails 15 are built up from sheet metal and for convenience are formed in two halves—an interior half 15—i and an exterior half 15—e. The two rail halves 15—e and 15—i are arranged to contact along their inner margins near the bottom (in the instance of the bottom rail as shown in Fig. 4), where they are held together by screws 16. Thereabove the inner faces of the rail halves are spaced apart to form a deep slot 17, and near the top of the rail halves the slot is enlarged to a wide slot portion 18. Corresponding slots in the side and top rails similarly open toward the subsash 13.

A sealing strip 19 is disposed in each slot 17 and is normally in sealing contact with the adjacent rail of the subsash 13. The ends of the sealing strip are normally in contact at the corners of the subsash by virtue of their being mitered, as shown in Fig. 6.

Each rail of the subsash 13 is preferably of extruded metal stock. Each rail is rabbeted for the reception of the glass 14, which is held in position by a glazing strip 20. The outer edge—the lower edge in Fig. 4—of each rail of the subsash is formed with a V-shaped groove 21, which receives the complementary V-edge 22 of the sealing strip 19.

The fitting of the sealing strips 19 into the

grooves 21 of the subsash serve the two-fold purpose of locking the subsash against rotation and effecting a weather seal between the subsash and the main sash.

5 The pivotal mounting of the subsash in the main sash is effected by a pair of pivot pins or trunnions 23 and 23' (Fig. 2). The lower pivot pin 23 is shown in Fig. 5. Its upper end is received in a counterbore 24 in the lower rail of 10 the subsash 13 at the medial point thereof. The pivot pin passes through a bore 25 in the lower sealing strip 19. The lower end of the pivot pin is received in the socket 26 of a socket block 27 interposed between the inner faces of the 15 sash halves 15-e and 15-i which define the walls of the slot 17. The block 27 is welded or otherwise fixed to one of the slot faces. The setting of the lower end of the pin 23 in the socket 26 affords a thrust bearing to carry the 20 weight of the subsash 13 and the pin 23 serves to keep the subsash 13 in a vertically fixed position in reference to the main sash.

A similar pivot pin 23' (Figs. 2 and 6) is employed in the respective upper rails of the main 25 sash and subsash in axial alignment with the lower pivot pin 23, and this upper pivot pin is similarly arranged and performs the same function except that, obviously, it does not necessarily bear the weight of the subsash.

30 I shall now describe the mechanism by which the four sealing strips are held in their normal closed position against the outer edge faces of the subsash, that is, held in the positions indicated in Figs. 4 and 5.

35 A controlling bar 28, preferably of channel shaped cross section, is disposed adjacent the bottom of each slot 17, as shown in Figs. 4 and 6. There are thus four control bars 28. Each control bar is mounted for limited longitudinal reciprocation by virtue of a plurality of cross pins 29 extending through the flanges of the channel shaped control bar 28 with their ends extending into slots 30 in those portions of the main sash halves 15-e and 15-i which define the slot 17.

40 The adjacent ends of the four control bars 28 are interconnected by short lengths of cable 31 which pass over pulleys 32 journaled in the corners of the slots 17 and within the corners of the outer sash, as best shown in Fig. 6. The four 50 bars 28 and their interconnecting cable lengths 31 thus form a composite endless chain, whereby when one of the bars 28 is shifted longitudinally, the other three bars are simultaneously shifted and to the same extent.

55 Each sealing strip 19 is operatively connected with the adjacent operating bar 28 by a set of links 33. The outer end of each link 33 is pivoted to the operating bar 28 by one of the pins 29, previously described. The inner end of each link 60 is pivotally connected to the sealing strip 19 by a cross pin 34. The ends of each cross pin 34 also pass through transverse slots 35 in the walls of the main sash rail halves which define the slot 17.

The slots 30 for the pins 29 are arranged longitudinally (in reference to the sash rail, sealing strip and operating bar 28), whereas the slots 35 for the pins 34 are arranged transversely. As a result, if the sealing strips are in the closed position of Fig. 6 and one of the bars 28 is shifted longitudinally, the outer end of each link 33 will be constrained to follow a longitudinal path in its slot 30, whereas the inner end of each link 33 will be constrained to follow a transverse outward path in its slot 35. Consequently the longitudinal shifting of the control bars is translated, by the

links 33 and their guiding slots, to an outward transverse movement of the sealing strips 19, whereby the sealing strips are drawn into their slots 17 and away from sealing and positioning engagement with the outer edge faces of the subsash 13.

Inasmuch as the four control bars 28 and their connecting cables 31 are arranged to form an endless unit, operating movement may be applied at any point. One expedient I have illustrated consists of a finger lug 36 attached to one of the control bars 28, as shown in Fig. 6. This lug extends through a slot in the face of the sash where the end of the lug is exposed to the interior of the building, as shown in Figs. 1 and 2. By pulling the lug 36 down the immediate bar 28 and consequently all the other bars 28 are shifted, which in turn transversely shifts the sealing strips 19 to their outer or released position. The lug 36 may be releasably held in either its closed or open position by a spring clip 37, as indicated in Fig. 6.

The upper and lower ends, respectively, of the clip form spring finger detents. When the bar 28 is in its upper position the upper spring finger engages the lower side of the lug 36. When the bar 28 is in its lower position, the lower spring finger engages the upper side of the lug. The spring of the fingers of the clip 37 yields to permit the lug being snapped from one position to the other.

Another expedient for effecting the shifting is to form the trunnions of one of the pulleys 32 with a square bore 38, as shown in Fig. 6.

A square key (not shown) may then be inserted through a suitable opening in the exposed face of the main sash and into the square bore 38 whereby the pulley 32 may be turned. The groove of the pulley should, of course, be conformed to afford more positive traction with the cable, or a chain and sprocket may be substituted for the cable and pulley. This key expedient has the advantage that the keys may be kept in the possession of the window washers of public buildings and factories, so that the pane will be rotated only for cleaning and the occupants or tenants will be forced to raise the sash for ventilation. When the rotatable sash constitutes a subsash within a main sash, it will be too light to stand the strains and abuse to which it would be subjected if it were frequently left open for ventilation.

In Fig. 8 I have illustrated an alternative method of interconnecting the four control bars 28 for simultaneous shifting. This is effected by means of a bell crank 39 in lieu of the cable 31 and pulley 32. The pivotal interconnection of the ends of the bell crank to the ends of the bars 28 will include a slightly transversely elongated slot, whereby the shifting of each control bar 28 may be maintained strictly rectilinear as guided by the slots 30.

The transverse outward shift applied to each sealing strip 19 by movement of the control bars 28, as previously described, withdraws the sealing strip into its slot 17 far enough to clear the outer edge of the adjacent rail of the subsash 13. The subsash is then free to rotate about its aligned pivot pins or trunnions 23 and 23'. This enables the window washer to clean both sides of the pane from the inside of the building.

Because the movement imparted to the sealing strip is strictly a transverse movement that is, a movement in a direction transverse to the length of the strip, and the transversely disposed pivot

pins 23 and 23' are slidable in reference to their transverse bores 25 in the upper and lower sealing strips, the presence of the pivot pins does not interfere with the transverse shifting of the sealing strips.

Preferably—although not necessarily—a weather stripping 40 is interposed between each sealing strip 19 and its slot 17. It is for this purpose that the mouth over each slot 17 is enlarged as indicated at 18. The weather stripping 40 may be of metal or other standard weather stripping construction which will permit the transverse shifting of the sealing strip 19. Preferably, however, the weather stripping 40 is of composite fabric and rubber packed into the slot 18 to maintain a weather seal between the slot and the sealing strip 19 without offering too much friction against shifting of the strip. On the exterior side—that is the side exposed to the weather—the weather stripping 40 is formed obliquely at its upper edge along the bottom rail of the main sash, as indicated in Fig. 4, and the chamfered upper edge of the lower rail half 15—e is lowered into oblique alignment therewith. The purpose is to direct water downwardly and away from the sealing strip 19 where it might freeze and offer excessive resistance to shifting. For the same purpose, I prefer to extend the lower exterior edge of the lower rail of the subsash 13 into an overhanging drip edge 13'. Water running down the pane and across the bottom rail of the subsash is thus carried across and beyond the line of contact between the exterior weather stripping 40 and the sealing strip 19.

As a further weather seal, I prefer to provide a resilient rubber strip 41 disposed within a square slot at the base of the V-shaped groove 21 in the edge face of the subsash 13. The rubber strip 41 is normally square or rectangular in cross section, but is deformed by the apex of the sealing strips 19, as shown in Fig. 4, which presents a particularly tight weather seal supplementing the contact of the mating V-shaped surfaces 21 and 22 on each side thereof.

The sealing strips 19 may be relatively light, even much lighter than here shown. Even though they may, therefore, have considerable flexibility, this flexibility does not interfere with the continuity and security of the seal they effect with the subsash. That is because inward pressure is applied to the sealing strip at relatively close intervals, depending upon how many links 33 are employed. The control bars are subject only to longitudinal strain and not to transverse strain; therefore, they may be relatively light also.

I contemplate that where so-called fixed windows are to be employed, such as in air-conditioned buildings and homes, the member corresponding to what I have here described as the main sash, may be a fixed sash, or in fact may be a part of the window frame. The rotatable subsash 13 may thus constitute the only movable sash, and be moved only for window cleaning.

While I have described and illustrated these specific embodiments of my invention, I contemplate that many changes and modifications may be made thereover without departing from the scope or spirit of my invention.

I claim:

1. A window comprising an inner sash, a sash-like member framing the inner sash, means for pivotally mounting the inner sash for rotation in the sash-like member, a sealing strip mounted in

the sash-like member along each side of the inner sash and having a weather sealing engagement with the inner sash, a control bar mounted along each side of the sash-like member for longitudinal reciprocation, and mechanism interconnecting each control bar with its respective sealing strip for shifting the sealing strip, the several control bars being interconnected for common longitudinal actuation to shift the sealing strips.

2. A window comprising an inner sash, a sash-like member framing the inner sash, means for pivotally mounting the inner sash for rotation in the sash-like member, a sealing strip mounted in the sash-like member along each side of the inner sash and having weather sealing engagement with the inner sash, a control bar extending along each side of the sash-like member and mounted therein for longitudinal reciprocation, means interconnecting the control bars for joint reciprocation, and mechanism interconnecting each control bar with its associated sealing strip for translating the longitudinal reciprocation of the control bars into transverse shifting of the sealing strips.

3. A window comprising an inner sash, a sash-like member framing the inner sash, means for pivotally mounting the inner sash for rotation in the sash-like member, a sealing strip mounted in the sash-like member along each side of the inner sash and having weather sealing engagement with the inner sash, a control bar extending along each side of the sash-like member and mounted therein for longitudinal reciprocation, means interconnecting the control bars for joint reciprocation, and mechanism interconnecting each control bar with its associated sealing strip for translating the longitudinal reciprocation of the control bars into transverse shifting of the sealing strips, said mechanism including a plurality of links connecting each control bar to its associated sealing strip.

4. A window comprising an inner sash, a sash-like member framing the inner sash, means for pivotally mounting the inner sash for rotation in the sash-like member, a sealing strip mounted in the sash-like member along each side of the inner sash and having weather sealing engagement with the inner sash, a control bar extending along each side of the sash-like member and mounted therein for longitudinal reciprocation, means interconnecting the control bars for joint reciprocation, and mechanism interconnecting each control bar with its associated sealing strip for translating the longitudinal reciprocation of the control bars into transverse shifting of the sealing strips, said mechanism including a plurality of links connecting each control bar to its associated sealing strip, and guide slots carried by the sash-like member confining the inner ends of the links to transverse movement and the outer ends of the links to longitudinal movement.

5. A window comprising an inner sash, an outer sash framing the inner sash, opposed pivot pins extending between the inner sash and outer sash for pivotally mounting the inner sash for rotation in the outer sash, an inwardly opening slot in each rail of the outer sash facing the respective rails of the inner sash, a sealing strip mounted in each slot, the juxtaposed faces of each sealing strip and its associated inner sash rail being formed with complementary sealing surfaces, a control bar disposed in each slot outwardly of the sealing strip, means for mounting the control bars for longitudinal reciprocation, means for interconnecting the control bars

to shift longitudinally together, mounting means for the sealing strips confining them to transverse movement, and a plurality of spaced links pivotally connected at their inner ends to the 5 sealing strips and at their outer ends to the control bars whereby longitudinal reciprocation of the control bars is translated into transverse shifting of the sealing strips, and a common manually operated member for simultaneously 10 shifting the control bars longitudinally to shift the sealing strips into and out of sealing engagement with the inner sash.

6. A window comprising an inner sash, a sash-like member framing the inner sash, means for 15 pivotally mounting the inner sash for rotation in the sash-like member, a sealing strip mounted in the sash-like member along each side of the inner sash and having weather sealing engagement with the inner sash, a control bar extending 20 along each side of the sash-like member and mounted therein for longitudinal reciprocation, means interconnecting the control bars for joint reciprocation, and mechanism interconnecting each control bar with its associated sealing strip 25 for translating the longitudinal reciprocation of the control bars into transverse shifting of the sealing strips, said control bar interconnecting means comprising pulleys within the corners of the sash-like member and lengths of cable connecting adjacent ends of the control bars and 30 passing over the respective pulleys.

7. A window comprising an inner sash, a sash-like member framing the inner sash, means for pivotally mounting the inner sash for rotation in the sash-like member, a sealing strip mounted 35 in the sash-like member along each side of the inner sash and having weather sealing engagement with the inner sash, a control bar extending along each side of the sash-like member and mounted therein for longitudinal reciprocation, 40 means interconnecting the control bars for joint reciprocation, and mechanism interconnecting each control bar with its associated sealing strip for translating the longitudinal reciprocation of the control bars into transverse shifting of the sealing strips, said control bar interconnecting 45 means comprising a bell crank within each corner of the sash-like member having its arms connected respectively to the adjacent ends of the associated control bars.

8. A window comprising an inner sash, a sash-like member framing the inner sash, means for pivotally mounting the inner sash for rotation in the sash-like member, a sealing strip mounted 55 in the sash-like member along each side of the inner sash and having weather sealing engagement with the inner sash, a control bar extending along each side of the sash-like member and mounted therein for longitudinal reciprocation, 60 means interconnecting the control bars for joint reciprocation, and mechanism interconnecting each control bar with its associated sealing strip for translating the longitudinal reciprocation of the control bars into transverse shifting of the sealing strips, and a finger piece connected to one 65 of the control bars and exposed for manual manipulation exteriorly of the sash-like member for simultaneously operating all of the control bars to shift all of the sealing strips.

9. A window comprising an inner sash, a sash-like member framing the inner sash, means for pivotally mounting the inner sash for rotation in the sash-like member, a sealing strip mounted 70 in the sash-like member along each side of the inner sash and having weather sealing engagement

5 movement with the inner sash, a control bar extending along each side of the sash-like member and mounted therein for longitudinal reciprocation, means interconnecting the control bars for joint reciprocation, and mechanism interconnecting each control bar with its associated sealing strip for translating the longitudinal reciprocation of the control bars into transverse shifting of the sealing strips, a finger piece connected to one of the control bars and exposed for manual manipulation exteriorly of the sash-like member for simultaneously operating all of the control bars to shift all of the sealing strips, and a spring clip for yieldably holding the finger piece in its closed and in its opened positions.

10. A window comprising an inner sash, a sash-like member framing the inner sash, means for pivotally mounting the inner sash for rotation in the sash-like member, an inwardly opening slot 20 in each rail of the sash-like member, a sealing strip disposed in each slot and transversely shiftable therein, the outer face of each rail of the inner sash having a V-groove extending therealong, the inner face of each sealing strip having a longitudinally extending V-edge for sealing cooperation therewith, a longitudinally extending slot formed in the apex of the V-groove of each rail of the inner sash, and a strip of resilient sealing material disposed therein, the parts being so constructed and arranged that 30 when the sealing strips are in their inner or closed positions the apex of the V-edge of each sealing strip seals against said sealing material, and the oblique sides laterally thereof seal against the surfaces of the V-groove of the inner sash rail.

11. A window comprising an inner sash, a sash-like member framing the inner sash, means for pivotally mounting the inner sash for rotation in the sash-like member, a sealing strip mounted 40 in the sash-like member along each side of the inner sash and having weather sealing engagement with the inner sash, a control bar extending along each side of the sash-like member and mounted therein for longitudinal reciprocation, means interconnecting the control bars for joint 45 reciprocation, and mechanism interconnecting each control bar with its associated sealing strip for translating the longitudinal reciprocation of the control bars into transverse shifting of the sealing strip, said mechanism including a plurality 50 of parallel spaced links, the outer end of each link being pivotally connected to the control bar and the inner end of each link being pivotally connected to the sealing strip, the construction and arrangement being such that the links occupy a transverse position in reference to the associated bar and strip when the sealing strips are in their closed or sealing position, but occupy an oblique position when the sealing strips are in their outer positions.

12. A window comprising an inner sash, a sash-like member framing the inner sash, means for pivotally mounting the inner sash for rotation in the sash-like member, an inwardly facing slot 65 in each rail of the sash-like member, a sealing strip mounted in each slot along each side of the inner sash and having weather sealing engagement therewith, a control bar in each slot outwardly of the sealing strip, and mounted in the slot for longitudinal reciprocation, means interconnecting the control bars for joint reciprocation, and mechanism interconnecting each control bar with its associated sealing strip for translating the longitudinal reciprocation of the control bars into transverse shifting of the seal- 75

ing strips, said mechanism including a plurality of spaced parallel links, an outer pivot pin connecting the outer end of each link to the associated control bar, an inner pivot pin connecting the inner end of each link with the associated sealing strip, a longitudinal slot for each outer pivot pin formed in the wall of the strip-receiving slot for confining the outer pivot pins to longitudinal movement, and a transverse slot for each inner pivot pin formed in the wall of the strip-receiving slot for confining the inner pivot pins to transverse movement, the construction and arrangement of the mechanism being such that when the sealing strips are in their inner or sealing position the links are disposed transversely to hold the sealing strips in sealing position under endwise thrust of the links.

13. A window comprising an inner sash, an outer sash-like member framing the inner sash, means for pivotally mounting the inner sash for rotation in the sash-like member, an inwardly opening slot in each rail of the sash-like member, a sealing strip mounted for transverse movement in each slot, the inner edge of each sealing strip being conformed for weather sealing engagement with the outer edge of each rail of the inner sash, a strip of weather sealing material in the mouth of each slot and interposed between the wall of the slot and the side of the associated sealing strip for sealing the movable strip to the sash-like member, and means for transversely shifting the sealing members into and out of sealing engagement with the inner sash.

14. A window comprising an inner sash, an outer sash-like member framing the inner sash, means for pivotally mounting the inner sash for rotation in the sash-like member, an inwardly opening slot in each rail of the sash-like member, a sealing strip mounted for transverse movement in each slot, the inner edge of each sealing strip being conformed for weather sealing engagement with the outer edge of each rail of the inner sash, a strip of weather sealing material in the mouth of each slot and interposed between the wall of the slot and the side of the associated sealing strip for sealing the movable strip to the sash-like member, and means for transversely shifting the sealing members into and out of sealing engagement with the inner sash, the lower edge of the lower rail of the inner sash, along its weather exposed side, having a drip lip overhanging the line of contact between the weather sealing material and the sealing strip to divert water therefrom.

15. A window comprising an inner sash, an outer sash-like member framing the inner sash, a slot formed in each rail of the sash-like member and facing the outer edge of the adjacent rail of the inner sash, a sealing strip shiftably mounted in each slot for sealing engagement with the outer edge of the adjacent rail of the inner sash, mechanism operating upon the sealing strips independently of substantial lateral thrust thereon in a direction perpendicular to the plane of the outer sash-like member, for shifting the sealing strips transversely of themselves, but parallel with the plane of the outer sash-like member, and without substantial longitudinal movement, into and out of sealing engagement with the inner sash, and a pair of aligned pivot pins disposed in opposed slots for journaling the inner sash for rotation within the outer sash-like member, each pivot pin passing through a hole in its adjacent

sealing strip whereby the associated sealing strips may be transversely shifted independently of the pivot pins.

16. A window comprising an inner sash, an outer sash framing the inner sash, means for pivotally journaling the inner sash for rotation within the outer sash, each rail of the outer sash comprising an interior (indoor) half and a generally similar exterior (outdoor) half, means for holding the halves assembled and providing an inwardly opening slot between the halves in a central plane of the outer sash, a sealing strip mounted in each slot for shifting, transversely of itself, and relative to the outer sash, into and out of sealing engagement with the inner sash, and mechanism substantially concealed within the slots for shifting the strips into and out of sealing engagement with the inner sash.

17. A window comprising a rigid rectangular outer sash, a rigid rectangular inner sash pivotally mounted therein about a medial axis, window glass rigidly carried by the inner sash, a set of sealing strips disposed along the respective sides of the sash and intermediate the inner and outer sash for sealing the inner sash to the outer sash, the sealing strips, when in their sealing position, sealing throughout the margin of the inner sash including its corners and the respective strips abutting at the corners, and mechanism including a common manually engageable member for shifting the strips transversely of themselves outwardly from the inner sash to release their seals with the inner sash.

18. A window comprising a main sash, a sub-sash mounted therewithin to pivot about an axis closing the field of the sub-sash, a set of four sealing strips operatively disposed between the main sash and sub-sash along the respective sides of the sub-sash, the window including common operating means for simultaneously shifting each sealing strip transversely of itself—under shifting pressure upon each strip applied thereto as a pressure substantially wholly parallel with the plane of the main sash—relative to the main sash, to the sub-sash and to the other strips, into and out of sealing engagement with the sub-sash, the strips when in sealing position intersealing the main sash and sub-sash continuously about the margins of the sub-sash, including its corners.

19. A window according to claim 18 wherein the operating means is mounted interiorly of the rails of one of the sashes and substantially concealed thereby.

20. A window according to claim 18 wherein the operating means and the strips are mounted in the rails of the main sash and the operating means is substantially concealed thereby.

21. A window according to claim 18 wherein the sealing strips are mounted in the main sash and the ends of the strips are mitered to form abutting miter joints when in sealing position.

22. A window according to claim 18 wherein the sealing strips and the operating means are mounted in the main sash and the ends of the strips are mitered for abutment when the strips are in sealing position, and wherein the operating means includes a bell crank at each corner with its fixed pivot on the sash substantially in the line of miter with an arm extending on each side of the line of miter and operatively connected with the adjoining sealing strip.
